FIG. 1

FIG. 2

FIG. 3

FIG. 4

FIG. 6

FIG. 5

FIGURE 1 is a front elevational view of a television remote control or similar article, showing my new design.

FIGURE 2 is a right side elevational view thereof;

FIGURE 3 is a top view thereof;

FIGURE 4 is a back view thereof;

FIGURE 5 is a bottom view thereof; and

FIGURE 6 is a left side elevational view partially in section.

The dominant features of my design reside in those portions of the drawing shown by means of full lines.

FIGURES 1 and 2 are shaded to indicate contrast in appearance in a preferred embodiment of my design.

I claim:

The ornamental design for a television remote control or similar article, substantially as shown and described.
